(57) CLAIM

The ornamental design for a lock for gooseneck trailer, as
shown and described.

DESCRIPTION

FIG. 1 is a perspective view of the lock for gooseneck trailer
of the present invention.

FIG. 2 is a rear view of the lock for gooseneck trailer of FIG.
1.

FIG. 3 is a front view of the lock for gooseneck trailer of
FIG. 1.

FIG. 4 is a bottom view of the lock for gooseneck trailer of
FIG. 1.

FIG. 5 is a top view of the lock for gooseneck trailer of FIG.
1; and,

FIG. 6 is a left-side view of the lock for gooseneck trailer of
FIG. 1.

The broken lines in all views are for illustrative purposes
only and form no part of the claimed design.
